UNITED STATES PATENT OFFICE.

IGNACIO TREVINO, OF ALICE, TEXAS

FISHING-TOOL.

1,172,180.

Specification of Letters Patent. Patented Feb. 15, 1916.

Application filed June 7, 1915. Serial No. 32,736.

To all whom it may concern:

Be it known that I, IGNACIO TREVINO, a citizen of the United States, residing at Alice, in the county of Jim Wells and State 5 of Texas, have invented new and useful Improvements in Fishing-Tools, of which the following is a specification.

This invention relates to a fishing tool primarily intended for use in connection with 10 wells for the purpose of removing broken well rods, or tools that become lost in the well during the drilling operation.

The primary object of the invention is the provision of a novel construction of a device 15 of this character whereby the well rod or tool will be effectively gripped, thus eliminating all possibility of the same from becoming disengaged from the device while being removed from the well.

Another object of the invention is the provision of a device of the above mentioned 20 character which can be made to accommodate well rods that vary in diameter, and the parts quickly assembled and disassembled as 25 the occasion may demand.

Among other features the invention embodies simplicity in construction, durability and efficiency for the purpose intended.

In the drawing forming a part of this 30 application like numerals of reference indicate similar parts in the several views and in which:

Figure 1 is a longitudinal sectional view showing the device in use. Fig. 2 is a similar view showing the normal position of the gripping members. Fig. 3 is a plan view. Figs. 4 and 5 are detail views of the gripping members.

Referring more particularly to the drawing A designates a well casing and B the well rod or tool desired to be removed.

The device forming the subject matter of the present invention essentially consists of a tubular member 5 having a longitudinal 45 bore 6 opening at both ends thereof, and diametrically opposed elongated slots 7.

Arranged within the bore 6 are the gripping members 8 and 9 respectively, each of which is provided with a stem 10 projecting 50 centrally therefrom through the slots 7, cotter pins 11 being passed through the stems to retain the gripping members operatively associated with the bar, the said members being supported for slight vertical pivotal 55 movement to permit the rod to pass therebetween and to be gripped thereby as the de-

vice is lowered into the well. The gripping member 8 comprises what may be termed a half disk having its gripping edge beveled at 12 while the member 9 is circular in outline and provided with a V-shaped opening, the edges of which are beveled as at 13. In normal position the adjacent edges of the gripping member are arranged in overlapped relation as shown in Fig. 2.

Screwed upon the lower end of the member 5 as at 14, or otherwise suitably secured thereto is a funnel-shaped member 15 which serves in the capacity of a guide for directing the rod into the bore 6 of the member 5 as the latter is being lowered into the well. Secured to the upper end of the member 5 through the medium of a coupling 16 is a short pipe extension 17, and fixed thereto is a hanger 18 to which one end of the cable 19 is secured.

In use the device is lowered into the well until the rod B enters the bore 6 whereupon it will engage the gripping members, slightly raising the latter so as to pass therebetween. The members 8 and 9 respectively then gravitate into engagement with the rod B in the manner shown in Fig. 1, and as will be readily obvious from this construction, the greater the pull upon the cable 19 in the 80 act of withdrawing the rod from the well, the more effectively will the members 8 and 9 grip the same. When very heavy pipes are to be raised from the well the extension 17 with the hanger 18 is removed, and a pipe 90 (not shown) of suitable length screwed into the end of the coupling 16. In order to permit the device to be used for removing the wooden rods, or rods of greater diameter than that shown it is only necessary to remove the funnel shaped member 15 and the gripping member 9, at which time the member 8 effectively grips the rod therebetween and the wall of the bore 6.

It is believed from the foregoing description the nature and advantages of the invention will be thoroughly understood without requiring a more extended explanation and therefore the same has been omitted. However I desire to have it understood that I do not limit myself to the precise construction illustrated, and that various changes may be made when desired as fall within the scope of the appended claims.

What I claim is: —

1. A device of the class described comprising a tubular member having a longitudinal

- bore and opposed elongated slots, gripping members mounted in said slots for vertical pivotal movement, one of said members comprising a half disk having a beveled edge, 5 the other of said members comprising a disk having a V-shaped opening extending to the periphery thereof, said members having their adjacent edges disposed in overlapped relation, a cone-shaped guiding element 10 detachably secured to the lower end of the member, and means for suspending the latter.

2. A device of the class described comprising a hollow tubular member having opposed longitudinally extending slots, gripping members arranged in overlapping relation within said tubular member, each of 15

said gripping members having a curved stem projecting through said slots and normally engaging the lower end wall of the latter, a 20 pin passed through said stem whereby each of said members is supported for pivotal movement, said tubular member being internally threaded adjacent its lower end, an, 25 exteriorly threaded cone-shaped element associated therewith, and means for suspending the device.

In testimony whereof I affix my signature in presence of two witnesses.

IGNACIO TREVINO.
